DECORATIVE ATTACHMENT FOR A BELT

Harry Rosenblatt, Brooklyn, N.Y., assignor to Ross Belts Inc., New York, N.Y., a corporation of New York

Filed July 20, 1965, Ser. No. 86,216

Term of patent 14 years

(Cl. D17—1)

FIG. 1.

FIG. 2.

FIG. 3.

FIG. 5.

FIG. 4.

FIG. 6.

I claim:

The ornamental design for a decorative attachment for a belt, as shown.
